US00D996606S

(12) **United States Design Patent** (10) **Patent No.:** **US D996,606 S**
(45) **Date of Patent:** **** Aug. 22, 2023**

(54) **INJECTOR**

(71) Applicant: **Owen Mumford Limited**, Woodstock (GB)

(72) Inventors: **Toby Cowe**, Woodstock (GB); **Tahir Shabudin**, Woodstock (GB); **Robert Hall**, Woodstock (GB)

(73) Assignee: **Owen Mumford Limited**, Oxfordshire (GB)

(**) Term: **15 Years**

(21) Appl. No.: **29/809,456**

(22) Filed: **Sep. 28, 2021**

(30) **Foreign Application Priority Data**

(57) **CLAIM**

The ornamental design for an injector, as shown and described.

DESCRIPTION

FIG. 1 is an isometric view of a front, top, and right side of an ornamental design for an injector in a first configuration; FIG. 2 is a front elevational view of the injector of FIG. 1; FIG. 3 is a right side elevational view of the injector of FIG. 1;

FIG. 4 is a top plan view of the injector of FIG. 1; FIG. 5 is a bottom plan view of the injector of FIG. 1; and, FIG. 6 is an isometric view of a front, top, and right side of the injector of FIG. 1 in a second configuration.

The dash-dash-dash lines are included for the purpose of illustrating portions of the injector that form no part of the claimed design.

1 Claim, 3 Drawing Sheets
